UNITED STATES PATENT OFFICE.

WALTER B. BARKS, OF COLUMBUS, OHIO, ASSIGNOR TO THE STROMBERG-CARLSON TELEPHONE MANUFACTURING COMPANY, OF ROCHESTER, NEW YORK, A CORPORATION OF NEW YORK.

DESIGN FOR A DIAL ESCUTCHEON FOR RADIO APPARATUS PANELS OR SIMILAR ARTICLE.

Application filed February 6, 1926. Serial No. 16,432. Term of patent 3½ years.

To all whom it may concern:

Be it known that I, WALTER B. BARKS, citizen of the United States, residing at Columbus, in the county of Franklin and State of Ohio, have invented a new, original, and ornamental Design for Dial Escutcheon for Radio Apparatus Panels or Similar Article, of which the following is a specification, reference being had to the accompanying drawing, forming part thereof.

The figure is a front plan view of a dial escutcheon for radio apparatus panels showing my new design.

I claim:

The ornamental design for a dial escutcheon for radio apparatus panels or similar article as shown.

W. B. BARKS.
